Primary Examiner—James Gandy*Assistant Examiner*—Linda Brooks**[57]****CLAIM**

The ornamental design for a media storage unit, as shown and described.

DESCRIPTION

FIG. 1 is a front, bottom, and side isometric view of a media storage unit showing my new design, it being understood that the opposite side view is substantially a mirror image thereof, the only difference being the screws on the rear and not on the front;

FIG. 2 is a rear, top, and side isometric view of FIG. 1, it being understood that the opposite side view is substantially a mirror image thereof, the only difference being the screws on the rear and not on the front;

FIG. 3 is a fragmentary sectional view taken along line 3—3 in FIG. 1;

FIG. 4 is a fragmentary sectional view taken along line 4—4 in FIG. 1; and,

FIG. 5 is a fragmentary sectional view taken along line 5—5 in FIG. 1.
